C. H. HOMEIER,
GAS SAVING DEVICE,
APPLICATION FILED MAR. 31, 1916.

Patented Jan. 9, 1917.

Inventor:
Charles H. Homeier
by: L. Brodman

Attorney.

UNITED STATES PATENT OFFICE.

CHARLES H. HOMEIER, OF ST. PAUL, MINNESOTA.

GAS-SAVING DEVICE.

1,211,583.

Specification of Letters Patent. Patented Jan. 9, 1917.

Application filed March 31, 1916. Serial No. 88,129.

To all whom it may concern:

Be it known that I, CHARLES H. HOMEIER, a citizen of the United States, residing at St. Paul, in the county of Ramsey and State 5 of Minnesota, have invented a new and useful Improvement in Gas-Saving Devices, of which the following is a specification.

An object of this invention is the production of a gas saving device, which is simple and inexpensive in construction and effective in use.

More particularly this invention relates to that class of gas saving devices, which is adapted to effect a saving of gas by regulating its pressure at or near the point of use.

To these ends my invention comprises the features of construction and combination of parts hereinafter more particularly described and claimed.

20 In the accompanying drawing forming part of this specification, Figure 1 is a longitudinal section of my invention; Fig. 2 is a section on the line X—X of Fig. 1, and Fig. 3 is a section of a detail.

25 In the drawing, A represents a cap having a cylindrical side wall or body 2 and a perforated end wall 3.

4 indicates a disk or plate, which is pivoted by the pivot 5 centrally disposed through 30 the end wall 3 and said disk, whereby the disk may be swiveled. The disk 4 is provided with a plurality of perforations 6, which are adapted to register with the perforations 7, in the end wall, but which may 35 be moved out of partly registering position in order to primarily regulate the amount of gas passing through the perforations and said cap. The outer end of the cap has an internal thread 8 by which a thimble B is 40 secured axially thereon. Said thimble has an outer end wall 9 provided with a plurality of perforations 10, which allow the gas to pass freely through the chamber formed by the cap and thimble.

45 In use the structure described is adapted to be clamped with the cap secured between the ends of two adjacent sections, 11 and 12, of piping, and within a union 13, which is threaded upon and couples said sections together. In this position, the regulating disk 4 is clamped in regulating position securely upon the end wall 3 and the entire structure is held firmly within the conducting duct by which a current of gas is supplied in the 50 direction of the arrows indicated in Fig. 1

of the drawing. The end of the cap is placed with its end 3 facing the current of gas; so that the gas is admitted through the perforations 7 into the chamber within the regulator and passes outwardly from said chamber through the perforations 10.

Arranged within the chamber formed by the cap and thimble is a diaphragm 14 in the form of a disk of slightly less diameter than the inner diameter of the cap. This 65 diaphragm is mounted upon the free end of a weak helical spring 15 extending backwardly from the diaphragm toward the outlet end of the thimble where it is secured rigidly to and supported by a plate 16 of 70 sufficiently less diameter than the inner diameter of the thimble, to allow the gas to pass freely. The plate 16 to which said spring is secured such as by soldering or other suitable means is provided with a stud 75 bolt 17, which is threaded centrally through the end 9 of the thimble. This stud bolt is adjusted to regulate the tension of the spring 15 by engaging the bolt in the slot 18 and is locked in adjusted position by the 80 nut 19 threaded on said bolt. By turning the bolt 17 inwardly, the distance between the diaphragm 14 and the inner face of the end wall 3 is reduced, or the tension of the spring 15 against the onward current of gas 85 increased. This regulation is arranged in advance, so that the proper amount of gas is allowed to pass freely through the feed piping. If the pressure of the gas reduces the spring 15 automatically adjusts the dia- 90 phragm in front of the end of the thimble B and compensates for any uneven pressure. After the spring 15 and the plate 4 have been initially regulated the device requires no attention, the regulation being conducted 95 entirely automatically by the movement of the diaphragm on the spring 15. The dia- phragm 14 is secured to the end of the spring 15 by soldering or other suitable means, and the diaphragm is formed with 100 inwardly projecting lugs 20 (see Fig. 3) around which a coil of the spring compresses to assist in holding said parts together. The diaphragm is further formed with notches 21 in its periphery, in order that 105 the gas may pass the diaphragm more readily. The pivot 5 may project inwardly through the diaphragm to assist the latter in guiding freely.

The device is also adapted to regulate the 110

pressure of water and in using the term "gas" it is intended to include any gas or liquid.

In accordance with the patent statutes, I 5 have described the principles of operation of my invention, together with the apparatus which I now consider to represent the best embodiment thereof, but I desire to have it understood that the construction 10 shown is only illustrative, and that the invention can be carried out by other means and applied to uses other than those above set forth within the scope of the following claims.

15 Having described my invention, what I claim as new and desire to protect by Letters Patent is.

1. A device of the class set forth, comprising, in combination, a cap having a body 20 formed with a passaged end wall, a thimble in the form of a cylindrical casing mounted axially upon said cap, a diaphragm arranged freely adjacent the passaged end of said cap, a base plate adjustably mounted 25 upon the outer end of said thimble and adapted to be regulated inwardly within said thimble, and a coil compression spring having one end mounted upon said base plate and its other end secured to and re- 30 siliently supporting said diaphragm, said cap being adapted to be clamped between the adjacent ends of a pair of sections of piping with one end facing the onward flow of gas to intercept said current by said re- 35 siliently supported diaphragm.

2. A gas regulator, comprising, in combination, a cap having a body adapted to be clamped between the adjacent ends of a pair of sections of piping and an end wall pas-

saged to admit gas passing through said 40 piping, a perforated plate movably mounted upon said end and adapted to be held in initially regulated position by the clamping of said sections of piping together, a thimble carried by said cap having a perforated end, 45 a base within said thimble having a regulating element movably mounted in its end, a coil compression spring mounted upon said base within said thimble and extending longitudinally thereof and a diaphragm carried 50 by the free end of said spring adjacent the passaged end of said cap and adapted to intercept the flow of gas passing through said thimble and cap.

3. A gas regulator comprising, in combination, a cap having a body adapted to be clamped between the adjacent ends of a pair of pipe sections, said cap having an end wall provided with a plurality of openings for the passage of gas therethrough, a thimble 60 carried by said cap having a perforated end, and an abutment therein adjacent said end, a coil compression spring bearing at one extremity against said abutment, a dia- phragm carried by the free end of said 65 spring adjacent the passaged end of said cap and adapted to intercept the flow of gas passing through the thimble and cap, and a member movably disposed with respect to the end of said cap having openings therein 70 adapted to be brought into register with the openings in the end of the cap whereby the quantity of the flow of gas may be regulated to accord with the tension of the spring.

In testimony whereof, I have signed my 75 name to this specification.

CHARLES H. HOMEIER.

Copies of this patent may be obtained for five cents each, by addressing the "Commissioner of Patents, Washington, D. C."
